Thomas Eddy Jr. The Schedule referred to in the above Patent, and making part of the same _____ containing a description of the works of the said Thomas Eddy himself, of his Improvement in the construction for detecting a ~~making~~ known deficiency of water in steam Engine Boilers, called the Boiler:

Be it known that I Thomas Eddy of the City of New York, in the State of New York, have invented, an improved machine, for detecting, ~~making~~ known a deficiency of water in steam Engine Boilers, which consists a Boiler, in which the following is a full and exact description of the same, reference being had to the drawings accompanying this Specification, and which form a part thereof. At any convenient place on the top of a Boiler, a hole is drilled through and a stuffing box properly fitted to it, to admit a smooth metallic rod, of about half an inch diameter, to slide easily thru it, in a perpendicular direction, and without letting out the steam; the length of this rod may be about a foot longer than the distance between the top of the boiler and the surface of the water in it, when at its proper height. The lower end of this rod is attached so that it properly bears a flat and flat with the water in the boiler, and sufficiently heavy to overcome the friction of the rod thru the stuffing box. The upper part of the rod, that is, from its top to a little below where it enters the boiler, is made hollow, and a small hole is made into it, laterally, or at right angles to its length, near the bottom of the hollow part, and so as to communicate with that part; this hole (which is about one eighth of an inch diameter) is made at such part of the rod, as that when the water is at its proper height, this hole may be about half an inch above the boiler, or above that part of it, where it comes in contact with the steam; so that when the water sinks half an inch in the boiler, the steam (and so will sink also, and consequently bring the small hole inside of the boiler, thru which the steam will rush into the hollow part and escape at top, making known by its noise a deficiency of water within. To increase this noise, a bellows or whistle, the mouth of an organ pipe, a trumpet shaped tube, or other suitable instrument, may be fixed, to the top of the rod, and circumstances may require the mouth of the rod to be closed, through out its length. The part of the rod above of boiler may be ground, so that upon the eighth of water within may always be known, whether as well above the top of gauge rods, as when above them. When it is desired to clean the

piece of the Muffing box, I am aware of the case length, but from thence, and alone, than you are of an inch diameter, one end of this, for the length of two and a half inches, I turn down till it is only half an inch diameter, making the part of it conical where the small part joins the large, this conical part forms one half of a valve, the corresponding half is properly fitted to the top of a tube, with its face inwards, and a hole is drilled thro' its center, which admits the small end of the valve part, the rest of the conical part comes down up, and thus covering the steam tight. The lower end of the rod is attached to a float as before mentioned, that when the water sinks in the boiler, the float and rod sink also, and consequently opens the valve, through which the steam escapes, and gives, by its motion, motion of the rod. It is also to be observed in the construction of this valve, that, that part of the rod inside of the boiler, which connects the float to the valve, should be of one thickness throughout its length, and its diameter the same as that of the face of the valve:— for, if the area of this face or closing part of the valve be greater than the rods diameter, the pressure of the steam upon it, now as above that open the rod, would be in proportion to the difference:— and this pressure would also vary, as the density of the steam in the boiler changes:— consequently, it would derange the action of the float, and might prevent the valve from opening, and after the water had sunk below the float: and on the contrary, should the rod below the valve, be made larger than the face of it, the steam would have a constant tendency to open it. Whatever might be the quantity of water in the Boiler.
